UNITED STATES PATENT OFFICE

ADOLF P. SIMSON, OF MILWAUKEE, WISCONSIN, ASSIGNOR TO THE VITLER MANUFACTURING COMPANY, OF MILWAUKEE, WISCONSIN, A CORPORATION OF WISCONSIN

COMPRESSOR

Application filed July 31, 1931. Serial No. 554,259.

The present invention relates in general to improvements in the art of pumping fluids, and relates more specifically to improvements in the construction and operation of 5 variable capacity compressors.

An object of the invention is to provide an improved fluid pump which is simple and compact in construction, and which is moreover highly efficient in operation.

10 Another object of the invention is to provide a new and useful variable capacity compressor, the capacity of which may be readily varied at any time to meet various requirements.

15 A further object of the invention is to provide an improved capacity reduction mechanism which is especially applicable to reciprocable compressors of the type customarily employed in connection with refrigerating 20 systems.

These and other objects and advantages will be apparent from the following detailed description.

A clear conception of an embodiment of 25 the invention and of the mode of constructing and of manipulating devices built in accordance therewith, may be had by referring to the drawing accompanying and forming a part of this specification in which like reference characters designate the same or similar parts in the various views.

Fig. 1 is a part sectional fragment of a vertical twin cylinder single acting gas compressor showing several of the discharge 30 valves and the improved capacity varying mechanism;

Fig. 2 is a fragmentary sectional view showing the capacity varying mechanism in another position of adjustment; and

40 Fig. 3 is a similar fragmentary sectional view showing the capacity varying mechanism in still another position of adjustment.

The vertical twin cylinder single acting compressor specifically illustrated in the drawing, comprises in general a pair of laterally adjacent vertical cylinders 5 each having a reciprocable piston 6 therein, and having a common outlet passage 7 communicable with the piston displacement chambers 8 past series of discharge valves 9 of well-

known construction. The inlet valves for admitting the gases to the displacement chambers 8, are not shown, being of well-known construction and located in the piston 6. The cylinders 5 are provided with removable cylinder heads 10, and the ends of the cylinders adjacent to the discharge valves 9 and outlet passage 7, may be surrounded by a jacket 11.

The discharge valves 9 coat with seatings 12 formed on movable end plates 12, and these plates are normally held in the position shown in Fig. 1, by means of stiff springs 13 coating with members 14 which engage the upper ends of the plates 12. Casings 15 which are secured to the plates 12 concentrically of the cylinders 5, form lower and upper displacement chambers 16, 17, the lower of which are adapted to be placed in direct communication with the adjacent piston displacement chambers 8 through ports 18 in the plates 12, and the upper of which are directly communicable under certain conditions of operation, with the adjacent lower chambers 16 through ports 19. Each set of lower and upper ports 18, 19 is controllable by means of a double seated valve 20 secured to a stem 21 having screw thread engagement with a sleeve 22 formed integral with the corresponding casing 15, the plate 12, casing 15, valve 20 and stem 21 of each set being simultaneously movable when the corresponding spring 13 is compressed. Each valve 20, may however be adjusted to either close the port 18 as shown in Fig. 1, or to open the port 18 and close the port 19 as shown in Fig. 2, or to open both of the ports 18, 19 as shown in Fig. 3, by virtue of the screw thread coaction at the sleeve 22 and with the aid of a rotary stem 23 having a central socket coacting with the squared end 24 of the valve stem 21.

Each stem 23 is prevented from rising relative to the adjacent cylinder head 10, by means of the flange 25 at the lower end of the stem, and may be rotated to adjust the adjacent valve 20, by means of a hand wheel 26 secured to the upper stem end.

During normal operation of the compressor, and with the valves 20 set as shown in Fig. 1, the pistons 6 are reciprocated to

alternately admit gas to the displacement chambers 8 thereof, and to deliver the compressed gases past the discharge valves 9 to the common outlet passage 7. In case the pressure within one of the displacement chambers 8 cannot be sufficiently relieved by the opening of the discharge valves 9, the entire plate 12 and the elements associated therewith, will be lifted against the action of the corresponding spring 13, to thereby provide an annular relief opening extending entirely around the upper end of the cylinder 5 and communicating with the passage 7.

Should it become desirable to partially reduce the capacity of the compressor, one or both of the double seated valves 20 may be adjusted by manipulation of the hand wheels 26, to the position shown in Fig. 2, such adjustment being possible during normal operation of the compressor. When a valve 20 has been thus positioned, a portion of the gas admitted to the corresponding cylinder displacement chamber 8 passes freely past the port 18 into the lower chamber 16 of the casing 15 and increases the compression space or chamber 8 by the volume of the chamber 16. The volumetric capacity of the machine is thus immediately reduced. If only one of the valves 20 is adjusted to the position shown in Fig. 2, and the other is maintained in the position shown in Fig. 1, the volumetric capacity of the machine is reduced by the minimum possible amount. By setting both valves 20 as shown in Fig. 2, a greater reduction in capacity is obtained.

If it is desired to still further reduce the capacity, one or both of the valves 20 may be set as shown in Fig. 3, so that both of the ports 18, 19 are uncovered. With such setting of the valves 20, both chambers 16, 17 are placed into communication with the corresponding piston displacement chambers 8, and serve to correspondingly enlarge the latter. Only one valve 20 may be positioned as shown in Fig. 3 and the other may be set as shown in Fig. 2, or as shown in Fig. 1, thus making it possible by proper design of the casings 15, to secure any desired reduction in capacity with relatively few adjustments of the valves 20.

The casings 15 are movable with the plates 12 without disturbing the settings of the valves 20 and the positions of the stems 23. The construction is greatly simplified by disposing the casings 15 concentric relative to the cylinders 5, and by likewise disposing the ports 18, valves 20 and the stems 21. The squared ends 24 of the stems 21 furthermore provide spline connections which permit the stems 21 to move longitudinally relative to the upper stems 23, while permitting unobstructed rotation of the former by the latter.

From the foregoing description, it will be apparent that the present invention provides a simple and compact compressor structure

applicable to machines of various sizes and types. The capacity of machines equipped with the improvement may be readily varied to any desired extent without interrupting the operation of the machines, and without danger, and the invention has proven highly successful in commercial operation.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:—

1. In combination, a cylinder, a piston movable in said cylinder to compress fluid therein, means forming a plurality of chambers, and a valve for placing one or more of said chambers in open communication with the displacement chamber of said piston and cylinder.

2. In combination, a cylinder, a piston reciprocable in said cylinder to compress fluid therein, a casing forming a pair of chambers, and a valve movable axially of said cylinder to place one or both of said chambers in open communication with the displacement chamber of said piston and cylinder.

3. In combination, a cylinder, a movable plate coacting with an end of said cylinder, a piston movable within said cylinder toward said plate, means forming a pair of chambers movable with said plate, and a valve movable with said plate and adjustable independently thereof to place one or both of said chambers in open communication with the displacement chamber of said piston and cylinder.

4. In combination, a cylinder, a piston reciprocable in said cylinder to compress fluid therein, a casing forming a pair of chambers, a valve movable axially of said cylinder to bring one or both of said chambers in open communication with the displacement chamber of said piston and cylinder, and means accessible from the exterior of said cylinder for manipulating said valve.

5. In combination, a cylinder, a movable plate coacting with an end of said cylinder, a piston movable within said cylinder toward said plate, means forming a pair of chambers movable with said plate, a valve movable with said plate and adjustable independently thereof to place either one or both of said chambers in open communication with the displacement chamber of said piston and cylinder, and means accessible from exterior of said cylinder for adjusting said valve.

6. In combination, a cylinder, a movable plate associated with an end of said cylinder, a piston movable within said cylinder toward and away from said plate, a casing secured to

and movable with said plate, said casing forming a pair of chambers, and a valve movable axially of said cylinder to place one or both of said chambers in open communication with the displacement chamber of said piston and cylinder.

5 7. In combination, a cylinder, a movable plate associated with an end of said cylinder, said plate having discharge valves therein, a 10 spring for normally maintaining said plate in fixed position, means forming a pair of chambers movable with said plate, and a valve adjustable relatively to said plate to place either one or both of said chambers in 15 communication with the displacement chamber of said piston and cylinder.

8. In combination, a cylinder, a piston reciprocal in said cylinder, a casing disposed coaxial relative to said cylinder and forming 20 a pair of chambers, and a valve disposed coaxial with said chambers and movable axially of said cylinder to place one or both of said chambers in open communication with the displacement chamber of said piston and 25 cylinder.

9. In combination, a cylinder, a piston movable in said cylinder, a casing forming a pair of chambers, one of said chambers being located remote from said cylinder and 30 the other being disposed between said remote chamber and said cylinder, and a single valve movable axially of said cylinder to place first both of said chambers and then only one of said chambers in communication with 35 the displacement chamber of said piston and cylinder.

10. In combination, a cylinder, a piston movable in said cylinder, a casing having a 40 partition dividing the same into two chambers, one of said chambers being disposed directly adjacent to said cylinder and the other being disposed remote therefrom, and a valve movable away from said cylinder toward said partition to place first both of 45 said chambers in communication with the displacement chamber of said cylinder and to subsequently place only the nearest of said chambers in communication with the displacement chamber of said cylinder.

50 55 In testimony whereof, I affix my signature.
ADOLF P. SIMSON.

CERTIFICATE OF CORRECTION.

Patent No. 1,867,681.

July 19, 1932.

ADOLF P. SIMSON.

It is hereby certified that the name of the assignee in the above numbered patent was erroneously described and specified as "The Vitler Manufacturing Company", whereas said name should have been described and specified as The Vilter Manufacturing Company, as shown by the records of assignments in this office; and that the said Letters Patent should be read with this correction therein that the same may conform to the record of the case in the Patent Office.

Signed and sealed this 22nd day of November, A. D. 1932.

M. J. Moore,
Acting Commissioner of Patents.
